[57] CLAIM

The ornamental design of a confectionary holder, as shown and described.

DESCRIPTION

FIG. 1 is a perspective view of a confectionary holder showing our new design; shown without caps;

FIG. 2 is a left side elevational view thereof; shown with caps;

FIG. 3 is a top plan view thereof;

FIG. 4 is a left side elevational view thereof; shown without caps;

FIG. 5 is a top plan view thereof;

FIG. 6 is a right side elevational view thereof;

FIG. 7 is a top plan view of a top cap;

FIG. 8 is a top plan view of a bottom cap;

FIG. 9 is a sectional elevational view of a top cap, taken along line 7—7 of FIG. 7;

FIG. 10 is an inverted perspective view of a top cap;

FIG. 11 is a perspective view of a top cap; and,

FIG. 12 is a perspective view of a bottom cap.

FIGS. 2—6 and 9—12 are drawn in larger scale. The top and bottom caps are shown separately for clarity of illustration.
